US0D1047709S

(12) **United States Design Patent** (10) Patent No.: **US D1,047,709 S**
(45) Date of Patent: ** Oct. 22, 2024

(54) **MEASURING CUP**

(71) Applicant: **Hebei Fenger Intelligent Technology Co., Ltd.**, Shijiazhuang (CN)

(72) Inventors: **Jianzhong Zhang**, Handan (CN);
Xiaojia Liu, Handan (CN)

(73) Assignee: **Hebei Fenger Intelligent Technology Co., Ltd.**, Shijiazhuang (CN)

(**) Term: **15 Years**

(21) Appl. No.: **29/835,687**

(22) Filed: **Apr. 21, 2022**

(51) LOC (14) Cl. **10-04**

(52) U.S. Cl.

USPC **D10/46.2**; D7/543

(58) **Field of Classification Search**
